[57] **ABSTRACT**

A pressure-sensitive copying paper comprising an adsorbent solid acid and a microencapsulated color former capable of forming a distinct color when reacted with the adsorbent acid coated on the same or a different surface of a support or supports, the microencapsulated color former being at least one lactone compound derived from a pyridine-carboxylic acid represented by the formula;

or a mixture thereof, wherein A, A' and Y are as defined hereinafter, is disclosed.

2 Claims, No Drawings

PRESSURE-SENSITIVE COPYING PAPER
CONTAINING LACTONE COMPOUND OF
PYRIDINE CARBOXYLIC ACID

BACKGROUND OF THE INVENTION

1. Field of the Invention

The present invention relates to a pressure-sensitive copying paper using as a color former a pyridine-carboxylic acid lactone represented by the following general formula;

or a mixture thereof, wherein A and A', which may be the same or different, each represents a pyrrolyl, indolyl, carbazolyl, acridinyl, phenothiazinyl, thienyl, thianaphthetyl, julolidinyl or tetrahydroquinolyl group and Y represents a hydrogen atom, a lower alkyl group having 1 to 4 carbon atoms, a halogen atom or a phenyl group, with the proviso that A and A' both cannot simultaneously be an indolyl group or a pyrrolyl group.

2. Description of the Prior Art

In general, pressure-sensitive copying paper comprises the combination of an upper sheet (or transfer sheet) having coated on the back surface thereof minute microcapsules containing dissolved therein an electron donative substantially colorless organic compound capable of undergoing color reaction, i.e., color former, and a lower sheet paper (or receiving sheet) having coated on the surface thereof a color developer. When these two coated surfaces are brought into contact with each other and a localized pressure is applied to the assembly by handwriting or typewriting, microcapsules located at the pressure-applied area rupture and the organic color former contained in the organic solvent comes into contact with the color developer to form color.

Pressure-sensitive copying paper systems comprising the aforesaid transfer sheet and a receiving sheet and an intermediate sheet are also known. In these systems the middle sheet is usually coated, on opposite surfaces, with a layer of micro-capsules containing a color former solution and with a layer of a solid acid and a binder, respectively. Another type of pressure-sensitive copying system is a recording sheet which can be prepared by applying the above described microcapsules and the adsorbent solid acid on the same surface of a support.

As the color developer, there are active clay substances such as acid clay, attapulgite, zeolite, bentonite; solid organic acids such as succinic acid, tannic acid, benzoic acid; and acidic polymers such as phenol-formalin polymer, phenol-acetylene polymer, residual acid group-containing styrene-maleic anhydride polymer, salicylic acid-formalin polymer.

As the organic solvent for dissolving the color former, there are, such as ethylene glycol, chlorobenzenes, diphenyl chloride, diethyl phthalate, triethyl phosphate, alkynaphthalenes and naphthylalkyl alcohols.

SUMMARY OF THE INVENTION

As a result of detailed investigations on the color former for pressure-sensitive copying paper, the present inventors have discovered that there can be obtained a pressure-sensitive copying paper capable of forming an orange, red, purple, blue, green or a like color by using as a color former a novel pyridine-carboxylic acid lactone represented by the above formula (I), and that there can be obtained a pressure-sensitive copying paper capable of forming optional desired color by using the novel color former in combination with a known color former or formers.

15 DETAILED DESCRIPTION OF THE INVENTION

Pressure-sensitive copying papers using the novel pyridine-carboxylic acid lactone represented by the formula (I) is colorless or slightly colored before color reaction, but, when in contact with the color developer, it immediately forms orange, red, purple, blue, green or a like color with high color density.

The thus formed color is excellent in light resistance.

On the other hand, pressure-sensitive copying paper using the novel color former in combination with a known color former or formers immediately forms an optional color when brought into contact with the color developer. The thus formed color undergoes little change in hue with the lapse of time after color formation.

Now, representative examples of the color former, pyridine-carboxylic acid lactones represented by the formula (I) to be used for the pressure-sensitive copying paper of the present invention are given below.

Color Former	Chemical Term of Color Former
No. 1	2-[α -{9'-Ethylcarbazol-(3')-yl}- α -{1',2'-dimethylindol-(3')-yl}- α -oxy]-methyl-pyridine-carboxylic acid-(3) lactone
No. 2	3-[α -{9'-Ethylcarbazol-(3')-yl}- α -{1',2'-dimethylindol-(3')-yl}- α -oxy]-methyl-pyridine-carboxylic acid-(2) lactone
No. 3	An isomer mixture comprising 2-[α -{9'-ethylcarbazol-(3')-yl}- α -{1',2'-dimethylindol-(3')-yl}- α -oxy]-methyl-pyridine-carboxylic acid-(3) lactone and 3-[α -{9'-ethylcarbazol-(3')-yl}- α -{1',2'-dimethylindol-(3')-yl}- α -oxy]-methyl-pyridine-carboxylic acid-(2) lactone
No. 4	An isomer mixture comprising 2-[α -{9'-ethylcarbazol-(3')-yl}- α -{1'-methyl-2'-phenylindol-(3')-yl}- α -oxy]-methyl-pyridine-carboxylic acid-(3) lactone and 3-[α -{9'-ethylcarbazol-(3')-yl}- α -{1'-methyl-2'-phenylindol-(3')-yl}- α -oxy]-methyl-pyridine-carboxylic acid-(2) lactone
No. 5	An isomer mixture comprising 2-[α -{9'-ethylcarbazol-(3')-yl}- α -{1'-methyl-2'-phenyl-4'-chloroindol-(3')-yl}- α -oxy]-methyl-pyridine-carboxylic acid-(3) lactone and 3-[α -{9'-ethylcarbazol-(3')-yl}- α -{1'-methyl-2'-phenyl-4'-chloroindol-(3')-yl}- α -oxy]-methyl-pyridine-carboxylic acid-(2) lactone
No. 6	An isomer mixture comprising 2-[α -{9'-ethylcarbazol-(3')-yl}- α -{1',2',5'-trimethylindol-(3')-yl}- α -oxy]-methyl-pyridine-carboxylic acid-(3) lactone and 3-[α -{9'-ethylcarbazol-(3')-yl}- α -{1',2',5'-trimethylindol-(3')-yl}- α -oxy]-methyl-pyridine-carboxylic acid-(2) lactone
No. 7	An isomer mixture comprising 2-[α -{9'-ethylcarbazol-(3')-yl}- α -{1',2'-dimethyl-5'-methoxyindol-(3')-yl}- α -oxy]-methyl-pyridine-carboxylic acid-(3) lactone and 3-[α -{9'-ethylcarbazol-(3')-yl}- α -{1',2'-dimethyl-5'-methoxyindol-(3')-yl}- α -oxy]-methyl-pyridine-carboxylic acid-(2) lactone

Color Former   Chemical Term of Color Former

No. 8	An isomer mixture comprising 2-[α , α -di-{9'-ethylcarbazol-(3')-yl}- α -oxy]-methyl-pyridine-carboxylic acid-(3) lactone and 3-[α , α -di-{9'-ethylcarbazol-(3')-yl}- α -oxy]-methyl-pyridine-carboxylic acid-(2) lactone	5
No. 9	An isomer mixture comprising 2-[α -{julolidin-(6')-yl}- α -{1',2'-dimethylindol-(3')-yl}- α -oxy]-pyridine-carboxylic acid-(3) lactone and 3-[α -{julolidin-(6')-yl}- α -{1',2'-dimethylindol-(3')-yl}- α -oxy]-pyridine-carboxylic acid-(2) lactone	10
No. 10	An isomer mixture comprising 2-[α -{1'-methylpyrrol-(2')-yl}- α -{9'-ethylcarbazol-(3')-yl}- α -oxy]-methyl-pyridine-carboxylic acid-(3) lactone and 3-[α -{1'-methylpyrrol-(2')-yl}- α -{9'-ethylcarbazol-(3')-yl}- α -oxy]-methyl-pyridine-carboxylic acid-(2) lactone	15

No. 20	An isomer mixture comprising 2-[α -{1',2'-dimethylindol-(3')-yl}- α -{thiophen-(2')-yl}- α -oxy]-methyl-4-chloro-pyridine-carboxylic acid-(3) lactone and 3-[α -{1',2'-dimethylindol-(3')-yl}- α -{thiophen-(2')-yl}- α -oxy]-methyl-4-chloro-pyridine-carboxylic acid-(2) lactone	65
No. 21	An isomer mixture comprising 2-[α -{1',2'-dimethylindol-(3')-yl}- α -{thiophen-(2')-yl}- α -oxy]-methyl-6-phenyl-pyridine-carboxylic acid-(3) lactone and 3-[α -{1',2'-dimethylindol-(3')-yl}- α -{thiophen-(2')-yl}- α -oxy]-methyl-6-phenyl-pyridine-carboxylic acid-(2) lactone	

A general process for producing pyridine-carboxylic acid lactones is described below.

1. First, the starting material, pyridine-carboxylic acid, is produced as follows. 1.0 Mol of quinolinic anhydride represented by the following formula;

wherein Y is the same as defined in the formula (I) is reacted with 1.0 to 2.0 mols of a heterocyclic compound represented by the following formula;

wherein A is the same as defined in the formula (I), in 1 to 2.5 l of a volatile organic solvent such as carbon disulfide, tetrachloroethane, benzene, nitrobenzenes, or the like at a temperature of 10° to 110°C for 1 to 9 hours with 1.0 to 3.0 mols of a Friedel-Crafts catalyst such as zinc chloride or aluminum chloride.

Thereafter, the reaction mixture is cooled to room temperature and the above-described inert solvent is removed by decantation.

The resulting reaction product is poured into 2 to 6 l of ice-water or cold dilute aqueous hydrochloric acid to hydrolyze the catalyst. The precipitated solid is collected by filtration, washed successively with water and an alcohol or benzene. After drying, there is obtained an isomer mixture comprising a 2-(heterocyclic-carbonyl)-pyridine-carboxylic acid-(3) represented by the following formula;

wherein A and Y are the same as defined in the formula (I) and a 3-(heterocyclic-carbonyl)-pyridine-carboxylic acid-(2) represented by the following formula;

wherein A and Y are the same as defined in the formula (I).

If necessary, the above obtained isomer mixture may be separated into each of the isomers thereby obtaining a highly purified 2-(heterocyclic-carbonyl)-pyridine-carboxylic acid-(3) or 3-(heterocyclic-carbonyl)-pyridine-carboxylic acid-(2), or (heterocyclic-carbonyl)-pyridine-carboxylic acids in which two isomers are present in various proportions can be obtained by 1) dissolving the mixture in dilute aqueous sodium hy-

droxide, adding dilute aqueous hydrochloric acid to the resulting solution in small portions and recovering each of solids which separately precipitates due to the difference in pH or (2) repeatedly recrystallizing the mixture using a mixture of a less polar solvent such as benzene, toluene and the like and a polar solvent such as methanol, butanol and the like or (3) a combination of (1) and (2) above.

2. A pyridine-carboxylic acid lactone represented by the above formula (I) is produced as follows. 1.0 Mol of a mixture of isomers represented by the formulae (IV) and (V) and 0.9 to 1.5 mols of a heterocyclic compound represented by the formula (III) are added to concentrated sulfuric acid, acetic anhydride or polyphosphoric acid, and the reaction mixture is heated to a temperature of 50° to 130°C for 2 to 10 hours followed by cooling to room temperature. Then, the reaction product is poured into ice-water followed by adding thereto a dilute aqueous solution of sodium hydroxide to make the solution weakly acidic or neutral. To this is then added benzene, toluene or the like followed by stirring to transfer any unreacted heterocyclic compound to the benzene, toluene or a like layer. Then, the benzene or toluene layer is separated off. To the residual solution is added dilute aqueous sodium hydroxide to adjust the pH to 11 to 12. The precipitated solid is filtered off, washed successively with water and a small amount of an alcohol or benzene.

After drying, there is obtained a substantially colorless or slightly colored pyridine-carboxylic acid lactone represented by the formula (I) corresponding to the mixture of isomers represented by the formulae (IV) and (V) in high yield. Or else, after adding a dilute aqueous sodium hydroxide to the residual solution to adjust the pH to 11 to 12, benzene or toluene is added thereto followed by stirring to thereby transfer pyridine-carboxylic acid lactone to the benzene or toluene layer. Then, the benzene or toluene layer is separated out, and benzene or toluene is distilled off. The thus obtained residue is washed successively with water and a small amount of an alcohol or benzene.

After drying, there is obtained in high yield a substantially colorless or slightly colored pyridine-carboxylic acid lactone represented by the formula (I) corresponding to the mixture of isomers represented by the formulae (IV) and (V) used as the starting material. If necessary, the thus obtained pyridine-carboxylic acid lactone may be recrystallized.

The process for the production of the color former, pyridine-carboxylic acid lactone, according to the present invention will now be illustrated by reference to the following Examples.

PREPARATION EXAMPLE 1 (Color Former Nos. 1 and 2)

30 g of quinolinic anhydride and 75 g of 9-ethylcarbazole were added to 300 ml of benzene, and 80 g of anhydrous aluminum chloride was added to the resulting mixture in small portions at a temperature of 10° to 20°C for about 40 minutes while stirring.

After completion of addition, the mixture was allowed to react at a temperature of 40° to 50°C for 3 hours and thereafter cooled to room temperature. The benzene layer was removed by decantation, and the resulting reaction product was added to 2 l of a cold 2N aqueous hydrochloric acid followed by stirring. The precipitated solid was recovered by filtration, washed

with water and then a small amount of ethanol and dried to obtain 48.1 g of an isomer mixture comprising 2-[9'-ethylcarbazole-carbonyl-(3')]-pyridine-carboxylic acid-(3) and 3-[9'-ethylcarbazole-carbonyl-(3')]-pyridine-carboxylic acid-(2) as pale brown crystals having a melting point of 155° to 167°C.

40 g of the isomer mixture thus obtained (m.p., 155° to 167°C) was then dissolved in dilute aqueous sodium hydroxide, and the resulting solution was adjusted to a pH of 6 with dilute aqueous hydrochloric acid. The precipitated solid was filtered (the filtrate was set aside), washed with water and dried to give 28 g of an isomer mixture comprising predominantly 3-[9'-ethylcarbazole-carbonyl-(3')]-pyridine-carboxylic acid-(2) and a small amount of 2-[9'-ethylcarbazole-carbonyl-(3')]-pyridine-carboxylic acid-(3) as pale brown crystals having a melting point of 202° to 212°C. Several recrystallizations of 20 g of the above obtained crystals from a mixed solvent of benzene-methanol (1:1 by volume) gave 12.5 g of a highly purified 3-[9'-ethylcarbazole-carbonyl-(3')]-pyridine-carboxylic acid-(2) as substantially colorless crystals having a melting point of 215° to 217°C.

On the other hand, to the filtrate having a pH of 6 obtained from the above filtration was added dilute aqueous hydrochloric acid to adjust a pH to about 2. The precipitated solid was filtered, washed with water and dried to obtain 11.3 g of an isomer mixture comprising predominantly 2-[9'-ethylcarbazole-carbonyl-(3')]-pyridine-carboxylic acid-(3) and a small amount of 3-[9'-ethylcarbazole-carbonyl-(3')]-pyridine-carboxylic acid-(2) as pale brown crystals having a melting point of 156° to 162°C. 10 g of the isomer mixture thus obtained was then recrystallized several times using a mixed solvent of toluene-ethanol (1:1 by volume) to give 3.7 g of a highly purified 2-[9'-ethylcarbazole-carbonyl-(3')]-pyridine-carboxylic acid-(3) as pale yellow crystals having a melting point of 165° to 167°C.

3.7 g of the above obtained 2-[9'-ethylcarbazolecarbonyl-(3')]-pyridine-carboxylic acid-(3) (m.p., 165° to 167°C) and 1.6 g of 1,2-dimethylindole were added to 30 g of acetic anhydride and the mixture was allowed to react at a temperature of 120° to 125°C for 3 hours and thereafter cooled to room temperature. The reaction product was poured into 300 g of ice-water to hydrolyze the acetic anhydride while stirring. After completion of hydrolysis, 50 ml of benzene was added thereto. The aqueous layer of the mixture was adjusted to a pH of 6.5 with dilute aqueous sodium hydroxide to transfer any unreacted 1,2-dimethylindole to the benzene layer, which was then removed by separation. The residual aqueous solution was adjusted to a pH of 12 with dilute aqueous sodium hydroxide and the precipitated solid was recovered by filtration, washed successively with water and a small amount of ethanol and dried. There was obtained 3.8 g of a compound (color former No. 1) represented by the formula;

as slightly pale yellow-colored crystals having a melting point of 198° to 199°C.

2.5 g of the above obtained 3-[9'-ethylcarbazolecarbonyl-(3')]-pyridine-carboxylic acid-(2) (m.p., 215° to 217°C) and 1.1 g of 1,2-dimethylindole were added to 20 g of acetic anhydride, and the mixture was allowed to react at a temperature of 120° to 125°C for 4 hours followed by cooling to room temperature. The reaction product was poured into 200 g of ice-water to hydrolyze the acetic anhydride while stirring. After hydrolysis, 40 ml of benzene was added thereto, and the aqueous layer of the resulting mixture was adjusted to a pH of 6.5 with dilute aqueous sodium hydroxide to transfer any unreacted 1,2-dimethylindole to the benzene layer. The benzene layer was removed by separation, and 50 ml of benzene was added to the solution. The aqueous layer of the resulting mixture was adjusted to a pH of 12 with dilute aqueous sodium hydroxide and the benzene layer was recovered by separation. The benzene was distilled off from the benzene layer and the residue was washed successively with water and a small amount of ethanol and dried to give 2.5 parts by weight of a compound (color former No. 2) represented by the formula;

as pale yellow-colored crystals having a melting point of 211° to 212°C.

PREPARATION EXAMPLE 2 (Color Former No. 3)

3.7 g of the isomer mixture of a pyridine-carboxylic acid obtained in Preparation Example 1 (m.p., 155° to 167°C) and 1.6 g of 1,2-dimethylindole were added to 30 g of acetic anhydride, and the mixture was allowed to react at a temperature of 120° to 125°C for 4 hours

followed by cooling to room temperature. The reaction product was poured into 300 g of ice-water to hydrolyze the acetic anhydride while stirring. After hydrolysis, 50 ml of benzene was added to the resulting aqueous solution and the aqueous layer of the mixture was adjusted to a pH of 6.0 with dilute aqueous sodium hydroxide to transfer any unreacted 1,2-dimethylindole to the benzene layer which was then removed by separation. To the residual solution 50 ml of benzene was added again and the aqueous layer was adjusted to a pH

of 12 with dilute aqueous sodium hydroxide. The benzene layer was taken out by separation, and the benzene was distilled off from the benzene layer to obtain a residue, which was then washed successively with water and a small amount of ethanol and dried to give 3.9 g of a mixture of isomers (color former No. 3) represented by the formulae;

8

and

as pale brown crystals having a melting point of 180° to 188°C.

PREPARATION EXAMPLE 4 (Color Former No. 9)

3.0 g of quinolinic anhydride and 6.1 g of julolidine were added to 30 ml of benzene, and 8.3 g of anhydrous aluminum chloride was added to the mixture in small portions. After completion of addition, the mixture was allowed to react at a temperature of 45° to 50°C for 3 hours followed by cooling to room temperature. The reaction product was worked up in the same manner as described in Preparation Example 2 to give

PREPARATION EXAMPLE 4 (Color Former No. 9)

3.0 g of quinolinic anhydride and 6.1 g of julolidine were added to 30 ml of benzene, and 8.3 g of anhydrous aluminum chloride was added to the mixture in small portions. After completion of addition, the mixture was allowed to react at a temperature of 45° to 50°C for 3 hours followed by cooling to room temperature. The reaction product was worked up in the same manner as described in Preparation Example 2 to give

4.5 g of an isomer mixture comprising 2-[julolidine-carbonyl-(6')]-pyridine-carboxylic acid-(3) and 3-[julolidine-carbonyl-(6')]-pyridine-carboxylic acid-(2) as pale yellow colored crystals having a melting point of 228° to 239°C.

3.5 g of the above obtained isomer mixture and 1.8 g of 1,2-dimethylindole were added to 20 g of acetic anhydride, and the mixture was allowed to react at a temperature of 105° to 110°C for 2 hours. After completion of the reaction, the reaction product was worked up in the same manner as described in Preparation Example 2 to obtain 3.8 g of an isomer mixture (color former No. 9) represented by the formulae;

and

as pale brown crystals having a melting point of 229° to 235°C.

PREPARATION EXAMPLE 5 (Color Former Nos. 10 - 17)

In the same manner as described in Preparation Example 1 except that 1-methylpyrrole, acridine, phenothiazine, 10-methyl-phenothiazine, thiophene, thianaphthene or 1-methyl-2,3,4-trihydroquinoline in

place of 9-ethylcarbazole was reacted with quinolinic anhydride to prepare the following corresponding pyridine-carboxylic acid, respectively:

5 An isomer mixture comprising 2-[1'-methylpyrrole- carbonyl-(2')]-pyridine-carboxylic acid-(3) and 3-[1'-methylpyrrole-carbonyl-(2')]-pyridine-carboxylic acid-(2);

10 An isomer mixture comprising 2-[acridine-carbonyl-(2')]-pyridine-carboxylic acid-(3) and 3-[acridine-carbonyl-(2')]-pyridine-carboxylic acid-(2);

An isomer mixture comprising 2-[phenothiazine-carbonyl-(3')]-pyridine-carboxylic acid-(3) and 3-[phenothiazine-carbonyl-(3')]-pyridine-carboxylic acid-(2);

15 An isomer mixture comprising 2-[10'-methylphenothiazine-carbonyl-(3')]-pyridine-carboxylic acid-(3) and 3-[10'-methyl-phenothiazine-carbonyl-(3')]-pyridine-carboxylic acid-(2);

An isomer mixture comprising 2-(2'-thenoyl)-pyridine-carboxylic acid-(3) and 3-(2'-thenoyl)-pyridine-carboxylic acid-(2);

An isomer mixture comprising 2-[thianaphthene-carbonyl-(2')]-pyridine-carboxylic acid-(3) and 3-[thianaphthene-carbonyl-(2')]-pyridine-carboxylic acid-(2); or

25 An isomer mixture comprising 2-[1'-methyl-2',3',4'-trihydroxyquinoline-carbonyl-(6')]-pyridine-carboxylic acid-(3) and 3-[1'-methyl-2',3',4'-trihydroxyquinoline-carbonyl-(6')]-pyridine-carboxylic acid-(2).

30 Each of the above obtained isomer mixtures was then reacted with the corresponding heterocyclic compound, and the reaction product was worked up in the same manner as described in Preparation Example 2 to obtain the corresponding pyridine-carboxylic acid lactone, respectively, as crystals. The corresponding pyridine-carboxylic acids and heterocyclic compounds used in this example and the melting points and crystal appearance of the resulting pyridine-carboxylic acid lactones are shown in Table 2 below.

Table 2

Color Former	Isomer Mixture of Pyridine-carboxylic Acid	Heterocyclic Compound	Melting Point (°C)	Crystal Appearance
No. 10	2-[1'-Methylpyrrole-carbonyl-(2')]-pyridine-carboxylic acid-(3) and 3-[1'-Methylpyrrole-carbonyl-(2')]-pyridine-carboxylic acid-(2)	9-Ethylcarbazole	120-125	pale brown
No. 11	2-[Acridine-carbonyl-(2')]-pyridine-carboxylic acid-(3) and 3-[Acridine-carbonyl-(2')]-pyridine-carboxylic acid-(2)	9-Ethylcarbazole	240-247	pale brown
No. 12	2-[Acridine-carbonyl-(2')]-pyridine-carboxylic acid-(3) and 3-[Acridine-carbonyl-(2')]-pyridine-carboxylic acid-(2)	Thianaphthene	228-235	pale yellow
No. 13	2-[Phenothiazine-carbonyl-(3')]-pyridine-carboxylic acid-(3) and 3-[Phenothiazine-carbonyl-(3')]-pyridine-carboxylic acid-(2)	1,2-Dimethyl-indole	240-245	pale brown
No. 14	2-[10'-Methylphenothiazine-carbonyl-(3')]-pyridine-carboxylic acid-(3) and 3-[10'-Methylphenothiazine-carbonyl-(3')]-pyridine-carboxylic acid-(2)	1,2-Dimethyl-indole	155-165	pale brown
No. 15	2-(2'-Thenoyl)-pyridine-carboxylic acid-(3) and 3-(2'-Thenoyl)-pyridine-carboxylic acid-(2)	1,2-Dimethyl-indole	163-175	pale brown

Table 2-continued

Color Former	Isomer Mixture of Pyridine-carboxylic Acid	Heterocyclic Compound	Melting Point (°C)	Crystal Appearance
No. 16	2-[Thianaphthene-carbonyl-(2')]-pyridine-carboxylic acid-(3) and 3-[Thianaphthene-carbonyl-(2')]-pyridine-carboxylic acid-(2)	1,2-Dimethyl-indole	118-125	pale brown
No. 17	2-[1'-Methyl-2',3',4'-tri-hydroquinoline-carbonyl-(6')]-pyridine-carboxylic acid-(3) and 3-[1'-Methyl-2',3',4'-tri-hydroquinoline-carbonyl-(6')]-pyridine-carboxylic acid-(2)	1,2-Dimethyl-indole	197-210	pale yellow

PREPARATION EXAMPLE 6 (Color Former No. 18) 15 carboxylic acid-(3) and 3-[1',2'-dimethylindole-carbonyl-(3')]-4-chloro-pyridine-carboxylic acid-(2); or

An isomer mixture comprising 2-[1',2'-dimethylindole-carbonyl-(3')]-6-phenyl-pyridine-carboxylic acid-(3) and 3-[1',2'-dimethylindole-carbonyl-(3')]-6-phenyl-pyridine-carboxylic acid-(2).

In the same manner as described in Preparation Example 1 except that 3.3 g of 1,2,3,4-tetrahydroquinoline in place of 9-ethylcarbazole was reacted with 3.0 g of quinolinic anhydride to prepare 20 3.8 g of an isomer mixture comprising 2-[1',2',3',4'-tetrahydroquinoline-carbonyl-(6')]-pyridine-carboxylic acid-(3) and 3-[1',2',3',4'-tetrahydroquinoline-carbonyl-(6')]-pyridine-carboxylic acid-(2). 2.8 g of the thus obtained isomer mixture and 2.0 g of phenothiazine were added to 20 g of polyphosphoric acid, and the mixture was allowed to react at a temperature of 110° to 120°C for 5 hours. After completion of the reaction, the reaction product was worked up in the same manner as described in Preparation Example 2 to obtain 3.0 g of an isomer mixture (color former No. 18) represented by the formulae;

35 and order to produce pressure-sensitive copying papers using pyridine-carboxylic acid lactones represented by the formula (I) as a color former, there may be employed the methods well known in the art as described in U.S. Pat. Nos. 2,800,457 and 2,800,458, in which phenomenon of complex coacervation is utilized

40 to produce microcapsules. Generally, the color former is used in an amount of 0.5 to 5.0% by weight based on the aforesaid organic solvent such as ethylene glycol, benzene chloride, diphenyl chloride, diethyl phthalate, trioctyl phosphate, alkyl naphthalene, naphthylalkyl alcohol, etc.

45 The pressure-sensitive copying paper using pyridine-carboxylic acid lactone represented by the formula (I) will be now illustrated in greater detail by the following non-limiting examples of preferred embodiments of the present invention.

EXAMPLE 1

2.0 Grams of Color former Nos. 1-3 were taken up and treated as follows. Each color former was dissolved 50 in 100 g of naphthylalkyl alcohol, and 20 g of gum arabic and 160 g of water were added thereto at a temperature of 50°C to emulsify. To this emulsion were added 20 g of acid-treated gelatin and 160 g of water and, under stirring, acetic acid was added thereto to adjust the pH to 5. Then, 500 g of water was added thereto to allow coacervation to proceed. Thus, thick, liquid film of gelatin-gum arabic was formed around oil droplets of naphthylalkyl alcohol containing dissolved therein the color former. After adjusting the pH to 4.4, 4 g of a 37% formalin aqueous solution was added thereto to harden the above-described liquid film. Then, the system was cooled to 10°C and, after adding thereto dilute aqueous sodium hydroxide to adjust the pH to 9, it was allowed to stand for 5 to 6 hours to thereby complete encapsulation.

as pale yellow-colored crystals having a melting point of 253° to 262°C.

PREPARATION EXAMPLE 7 (Color Former Nos. 19-21)

In the same manner as described in Preparation Example 2 except that 4-methyl-quinolinic anhydride, 4-chloro-quinolinic anhydride or 6-phenyl-quinolinic anhydride in place of the quinolinic anhydride was reacted with 1,2-dimethylindole to prepare the following corresponding pyridine-carboxylic acid, respectively.

An isomer mixture comprising 2-[1',2'-dimethylindole-carbonyl-(3')]-4-methyl-pyridine-carboxylic acid-(3) and 3-[1',2'-dimethylindole-carbonyl-(3')]-4-methyl-pyridine-carboxylic acid-(2);

An isomer mixture comprising 2-[1',2'-dimethylindole-carbonyl-(3')]-4-chloro-pyridine-

The resulting microcapsule-containing liquid was applied to a paper by a coating method such as roll-coating, air knifecoating, etc. After drying, there was obtained a colorless coated paper (upper sheet paper). When this upper sheet paper was intimately superposed on a lower sheet paper having coated thereon an active clay substance as a color developer and a localized pressure was applied to the assembly by handwriting, a purple color was immediately formed on the lower sheet paper at the pressed area. The color density of developed purple was high. 10

There was observed almost no discoloration and fading of the thus developed purple color even when it was exposed directly to sunlight for a long period of time.

Alternatively, when the upper sheet paper was intimately superposed on a lower sheet paper having coated thereon an acidic organic polymer and a localized pressure was applied thereto by handwriting, a bluish purple color was immediately formed on the lower sheet paper at the pressure-applied area. 20

EXAMPLE 2

2.0 Grams of color former No. 4 was taken up and treated in the same manner as described in Example 1. After coating and drying, there was obtained a colorless upper sheet paper. 25

When this upper sheet paper was intimately superposed on a lower sheet paper having coated thereon an active clay substance as a color developer and a localized pressure was applied thereto by handwriting, there was immediately developed a blue color on the lower sheet paper at the pressed area. There was observed almost no discoloration nor fading of the thus developed blue color even when it was directly exposed to sunlight for a long period of time. Alternatively, when the upper sheet paper was intimately superposed on a lower sheet paper having coated thereon an acidic organic polymer as the color developer and a localized pressure was applied to the assembly by handwriting, there was immediately developed a blue color on the lower sheet paper at the pressed area. 35

EXAMPLE 3

2.0 Grams of color former Nos. 5-10 and 17 were taken up and each of them was treated in the same manner as described in Example 1. 45

After coating and drying there was obtained colorless upper sheet papers. Each of the resulting papers was intimately superposed on a lower sheet paper having coated thereon an acid clay substance as a color developer. When a localized pressure was applied to the assembly, a deep color image was immediately formed on the lower sheet paper at the pressed area. The image thus formed exhibited a sufficient stability to the lapse of time for practical use. The hues developed on the lower sheets are shown in Table 3 below. 50

Table 3

Color Former	Hue
No. 5	blue
No. 6	purple
No. 7	bluish purple
No. 8	green
No. 9	blue
No. 10	purple
No. 17	blue

EXAMPLE 4

2.0 Grams of color former Nos. 11-12 and 18 were taken up and each of them was treated in the same manner as in Example 1. 5

After coating and drying, there were obtained upper sheet papers. When each of the resulting papers was intimately superposed on a lower sheet paper having coated thereon an acid clay substance as a color developer and a localized pressure was applied to the assembly by handwriting, there was immediately developed a deep color on the lower sheet paper at the pressed area. The thus developed color images showed sufficient stability for practical use. The hues developed on the lower sheets are tabulated below. 15

Table 4

Color Former	Hue
No. 11	green
No. 12	reddish orange
No. 18	purple

EXAMPLE 5

2.0 Grams of Color former Nos. 13-16 and 19-21 were taken up and each of them was treated, coated and dried in the same manner as in Example 1. Thus, there were obtained colorless upper sheet papers. 30

When each of the resulting papers was intimately superposed on a lower sheet paper having coated thereon an acid clay substance as a color developer and a localized pressure was applied to the assembly by handwriting, there was immediately developed a red color image on the lower sheet paper at the pressed area. Almost no discoloration or fading of the thus developed red color was observed even when it was exposed directly to sunlight for a long period of time. When this upper sheet paper was superposed on a lower sheet paper having coated thereon an acidic organic polymer as a color developer and a localized pressure was applied to the assembly by handwriting, there was immediately developed a red color on the lower sheet paper. 35 40

EXAMPLE 6

2.3 Grams of color former No. 3, 0.3 g of o-hydroxybenzalacetophenone, 0.1 g of rhodamine B-anilinolactam, 0.1 g of malachite green-lactone and 0.2 g of benzoyl leuco methyleneblue were treated and 50 coated in the same manner as in Example 1 to prepare an upper sheet paper. When this upper sheet paper was superposed on a lower sheet paper having coated thereon an active clay substance as a color developer and a localized pressure was applied to the assembly by 55 handwriting, there was immediately developed a black color on the lower sheet paper. The thus developed black color scarcely underwent change in hue and fading.

While the invention has been described in detail and 60 with reference to specific embodiments thereof, it will be apparent to one skilled in the art that various changes and modifications can be made without departing from the spirit and scope thereof.

What is claimed is:

65 1. A pressure-sensitive copying paper comprising on a support a layer of an encapsulated color former and on the same or different support a layer of an electron-

accepting solid, said color former being a lactone compound derived from a pyridine-carboxylic acid, represented by the formula

or a mixture thereof, wherein A and A', which may be the same or different, each represents indolyl, carbazolyl, acridinyl, phenothiazinyl, thieryl, thianaphthenyl, julolidinyl or tetrahydroquinolyl group and Y represents a hydrogen atom, a lower alkyl group having 1 to 4 carbon atoms, a halogen atom or a phenyl group, with the proviso that A and A' both cannot simultaneously by an indolyl group.

2. The pressure-sensitive copying paper according to claim 1, wherein said color-former is a compound selected from the group consisting of:

2-[α -{9'-ethylcarbazol-(3')-yl}- α -{1',2'-dimethylindol-(3')-yl}- α -oxy]-methyl-pyridine-carboxylic acid-(3) lactone,

3-[α -{9'-ethylcarbazol-(3')-yl}- α -{1',2'-dimethylindol-(3')-yl}- α -oxy]-methyl-pyridine-carboxylic acid-(2) lactone,

an isomer mixture comprising 2-[α -{9'-ethylcarbazol-(3')-yl}- α -{1',2'-dimethylindol-(3')-yl}- α -oxy]-methyl-pyridine-carboxylic acid-(3) lactone and 3-[α -{9'-ethylcarbazol-(3')-yl}- α -{1',2'-dimethylindol-(3')-yl}- α -oxy]-methyl-pyridine-carboxylic acid-(2) lactone,

an isomer mixture comprising 2-[α -{9'-ethylcarbazol-(3')-yl}- α -{1',2'-dimethylindol-(3')-yl}- α -oxy]-methyl-pyridine-carboxylic acid-(3) lactone and 3-[α -{9'-ethylcarbazol-(3')-yl}- α -{1',2'-dimethylindol-(3')-yl}- α -oxy]-methyl-pyridine-carboxylic acid-(2) lactone,

an isomer mixture comprising 2-[α -{9'-ethylcarbazol-(3')-yl}- α -{1',2'-dimethyl-5'-methoxyindol-(3')-yl}- α -oxy]-methyl-pyridine-carboxylic acid-(3) lactone and 3-[α -{9'-ethylcarbazol-(3')-yl}- α -{1',2'-dimethyl-5'-methoxyindol-(3')-yl}- α -oxy]-methyl-pyridine-carboxylic acid-(2) lactone,

5 an isomer mixture comprising 2-[α , α -di-{9'-ethylcarbazol-(3')-yl}- α -oxy]-methyl-pyridine-carboxylic acid-(3) lactone and 3-[α , α -di-{9'-ethylcarbazol-(3')-yl}- α -oxy]-methyl-pyridine-

10 carboxylic acid-(2) lactone,

an isomer mixture comprising 2-[α -{1'-methylpyrrol-(2')-yl}- α -{9'-ethylcarbazol-(3')-yl}- α -oxy]-methyl-pyridine-

15 carboxylic acid-(3) lactone and 3-[α -{1'-methylpyrrol-(2')-yl}- α -{9'-ethylcarbazol-(3')-yl}- α -oxy]-methyl-pyridine-carboxylic acid-(2) lactone,

an isomer mixture comprising 2-[α -{acridin-(2')-yl}- α -{thianaphthen-(2')-yl}- α -oxy]-methyl-pyridine-

20 carboxylic acid-(3) lactone and 3-[α -{acridin-(2')-yl}- α -{thianaphthen-(2')-yl}- α -oxy]-methyl-pyridine-carboxylic acid-(2) lactone,

an isomer mixture comprising 2-[α -{10'-methylphenothiazin-(3')-yl}- α -{1',2'-dimethylindol-(3')-yl}- α -oxy]-methyl-pyridine-carboxylic acid-(3) lactone and 3-[α -{10'-methylphenothiazin-(3')-yl}- α -{1',2'-dimethylindol-(3')-yl}- α -oxy]-methyl-pyridine-carboxylic acid-(2) lactone,

an isomer mixture comprising 2-[α -{thiophen-(2')-yl}- α -{1',2'-dimethylindol-(3')-yl}- α -oxy]-methyl-pyridine-carboxylic acid-(3) lactone and 3-[α -{thiophen-(2')-yl}- α -{1',2'-dimethylindol-(3')-yl}- α -oxy]-methyl-pyridine-carboxylic acid-(2) lactone,

an isomer mixture comprising 2-[α -{thianaphthen-(2')-yl}- α -{1',2'-dimethylindol-(3')-yl}- α -oxy]-methyl-pyridine-carboxylic acid-(3) lactone and 3-[α -{thianaphthen-(2')-yl}- α -{1',2'-dimethylindol-(3')-yl}- α -oxy]-methyl-pyridine-carboxylic acid-(2) lactone, and

15 an isomer mixture comprising 2-[α -{1',2'-dimethylindol-(3')-yl}- α -{thiophen-(2')-yl}- α -oxy]-methyl-pyridine-carboxylic acid-(3) lactone and 3-[α -{1',2'-dimethylindol-(3')-yl}- α -{thiophen-(2')-yl}- α -oxy]-methyl-pyridine-carboxylic acid-(2) lactone.
